Attorney

UNITED STATES PATENT OFFICE

HERMAN BARTENBACH, OF PITTSBURGH, PENNSYLVANIA

INSTRUMENT CASE

Application filed June 6, 1928. Serial No. 283,271.

My invention relates to certain new and useful improvements in instrument cases, and while particularly illustrating and describing its embodiment in watch cases, it will be obvious that the invention may be successfully employed in connection with the housings and cases of pocket watches, wrist watches, stop watches, pedometers, calculating and tallying devices, meteorological and nautical instruments, and any other devices requiring transparent face covers to permit reading of scales and dials, and further having levers and spindles passing through the cases for the purpose of energizing, controlling, regulating, adjusting, or operating the housed mechanisms.

The primary object of the invention is to provide an instrument case of the character described which is impervious to moisture, fluids, gases, dust, grit or any other extraneous matter, thereby promoting and maintaining the utility, operation, accuracy, and life of instruments enclosed therein.

Further objects of the invention are to provide a device of the class stated, which is simple in its construction and arrangement, durable and efficient in its use, which will not alter the regulation superficial configurations and appearances, which may be readily embodied in cases already constructed as well as forming a component part of a new case structure, and which is comparatively inexpensive to manufacture and in its maintenance.

To the accomplishment of these and such other objects as may hereinafter appear, the invention consists of the novel construction, combination and arrangement of parts herein specifically described and illustrated in the accompanying drawing wherein is shown an embodiment of the invention, but it is to be understood that changes, variations and modifications may be resorted to that come within the scope of the claims hereunto appended.

In the drawing wherein like numerals of reference designate corresponding parts throughout the several views:

Figure 1 is an enlarged side view, partly in cross section, of a watch-case constructed in accordance with the invention.

Figure 2 is a fragmentary side view, partly in section, of a modified form thereof.

Figures 3, 4 and 5 are fragmentary, cross sectional views illustrating modifications in the passage arrangements of associated elements through the case.

Referring in detail to the drawing 1 denotes the hollow body portion of a watch case of conventional configuration. The front and rear of the body portion are formed with outwardly projecting, exteriorly threaded, annular flanges, respectively indicated at 2 and 3. The threaded flanges 2 and 3 are constructed and arranged in the usual manner, having their peripheries inset or spaced from the periphery of the body portion 1.

The bezel 4, carrying a beveled crystal 5, has a screw thread connection with the front flange 2, and the back cover 6 has a screw thread connection with the rear flange 3.

A gasket 7 is positioned against the outer edge of the front flange 2, and a similar gasket 8 is positioned against the outer edge of the rear flange 3. The gaskets 7 and 8 may be constructed from any suitable material to render the same resiliently compressible and moisture-proof.

The bezel 4, crystal 5, and body portion 1, are so constructed and arranged, that when the edge margin of the bezel 4 is seated tightly against the opposed edge margin of the body portion 1, the distance between the outer edge of the front flange 2 and the opposed edge margin of the crystal 5, is less than the thickness of the gasket 7 disposed therebetween. The relative diameters of the gasket 7 and the crystal 5 is such, that the peripheral edge of the latter extends approximately centrally of the width of the gasket 7, whereby the latter, when in the assembled position, overlaps the connection of the crystal 5 with the bezel 4. It is evident that when the bezel 4 is screwed tightly in place to the body portion 1, the interposed gasket 7 will be squeezed and compressed and thus provide a sealing medium preventing the entrance of any extraneous matter either through the connection of the crystal 5 with the bezel 4, or

through the connection of the latter with the

body portion 1, or between the crystal 5 and the body portion 1.

The inner face of the back cover 6 is provided with an annular bead 9, which is disposed to engage the gasket 8 centrally of its width. When the back cover 6 is screwed to position on the threaded flange 3, the gasket 8 will be compressed to exclude all matter through the connection of the back cover 6 with the body portion 1.

The connection of the crystal 5 with the bezel 4 forms a bead 10 in the inner side thereof. The construction and arrangement of the bead 10 and of the back cover bead 9, though not essential, are preferred owing to the greater efficiency and reliability of a combination of gasket sealing against surfaces of relatively small areas.

In addition to sealing the connections of the crystal 5, bezel 4, and back cover 6 with associated parts, in the manner stated, the resilient compression of the gaskets 7 and 8 establishes a lateral spreading action against the threaded engagement of the connections retardant to the release of the latter. While the gaskets 7 and 8 are herein illustrated and described as embodied in a case having a screw bezel and back cover, it is to be understood that provision of such gaskets are equally adaptable to bezels and back covers of the hinge and snap type.

To exclude extraneous matter from the case, through the opening provided for the passage of the stem 11, the body portion is formed with an interiorly threaded stuffing bore 12. The latter is provided with suitable packing 13 which is compressed by a gland nut 14. The gland nut 14 is preferably split and resilient to prevent its accidental disengagement from the compressing position in the stuffing bore 12.

Figures 4 and 5 illustrate modified means for sealing the stem passages. The embodiment shown in Figure 4 provides a body portion 15 formed with an exteriorly threaded neck 16. The latter is engaged by an interiorly threaded apertured cap 17 provided with packing 18 which is compressed by the adjustment of the cap nut 17 upon the neck 16. The disclosure in Figure 5 differs from the showing in Figure 4 in that the interiorly threaded cap 20 is formed integral with the body portion 22, and opens into the latter at its inner end. A special gland nut 19 is provided within the cap 20 for compressing the packing 21 in the latter. The gland nut 19 must, of course, be adjusted from within the body portion 22. This latter arrangement is especially practical and desirable in cases where the packing will wear as long or longer than the life of the associated mechanism, or intervals between normal repairs.

Figure 3 illustrates a method of packing two concentrically mounted passage members, respectively indicated at 24 and 25. The

member 24 is associated with a stuffing bore 26 formed in the body portion 27. The stuffing bore 26 is provided with packing 28 and a gland nut 29. The member 25 extends through the member 24 and is associated with a stuffing bore 30 formed in the latter. The stuffing bore 30 is provided with packing 31 and a gland nut 32. This arrangement permits of either the independent or synchronous operation of the members 24 and 25.

The arrangement of the packing with associated parts, as above described, is equally effective whether the required movements of the latter be longitudinal, reciprocating, rotary, or the combination of any or all of such movements.

Figure 2 discloses a modified embodiment for sealing the connection of the back cover 35 with the body portion 1. A gasket 33 is mounted in a groove 34 formed on the inner face of the edge margin of the back cover 35. The thickness of the gasket 33 is normally greater than the depth of the groove 34 and when the back cover 6 is screwed to position on the body portion 1, the gasket 32 will be compressed to adequately seal the connection therebetween.

The feature of the present invention resides in the provision for sealing the covers and the passage ways of associated spindles, levers, stems, etc., of instrument cases, to effectively exclude the potential entrance of moisture, excessive humidity, water, fluids, gases, dust and any other matter detrimental to the operation and accuracy of precision mechanisms. Watches, particularly, are worn in more or less close contact to the body and are liable to being entered by perspiration in warm weather, by water from soaked garments or by accidental immersion.

Wrist watches constructed in accordance with this invention could be worn, without damage thereto by divers, swimmers, bathers, traffic policemen, firemen, sailors, soldiers, and others who must be exposed to conditions that do not permit them to keep dry. Further, the invention is particularly adaptable for the protection of meteorological and nautical instruments that are necessarily exposed to most adverse weather and sea elements.

It will here be noted that the application of the present invention provides a most efficient instrument case, that does not, in any appreciable extent, change the superficial configuration or appearance of the latter, and therefore does not prevent or limit the use of possible attachments or other devices which might be employed to extend the field of usefulness of the instruments. Furthermore, because of this condition, it is not necessary to modify, in any way, the artistic finish, decorations, embellishment and elaborations of the improved case.

What I claim is:

1. In an instrument case of the character described, a hollow body portion including a removable bezel provided with a crystal member, and means for sealing the connections of said bezel with said crystal member and with said body portion for preventing the passage of all extraneous matter through said connections.
- 10 2. In an instrument case of the character described, a hollow body portion including a removable bezel provided with a crystal member, and a resiliently compressible element for sealing the connections of said bezel with said crystal member and with said body portion for preventing the passage of all extraneous matter through said connections.
- 20 3. In an instrument case of the character described, a hollow body portion including a removable bezel provided with a crystal member, and a resiliently compressible gasket for simultaneously sealing the connection of said crystal member with said bezel and the connection of said bezel with said body portion for excluding the entrance of all extraneous matter through said connections.
- 30 4. In an instrument case of the character described, a hollow body portion including a removable bezel provided with a crystal member, and a resiliently compressible gasket for simultaneously sealing the connection of said crystal member with said bezel and the connection of said bezel with said body portion for excluding the entrance of all extraneous matter through said connections, said gasket being disposed against said body portion and overlapping the connection of said bezel with said crystal member.

In testimony whereof I affix my signature.
